Primary Examiner — Cynthia Ramirez*Assistant Examiner* — Jeremy S. Swartz(74) Attorney, Agent, or Firm — Edell, Shapiro & Finnian, LLC(57) CLAIM

The ornamental design for a bassinet, as shown and described.

DESCRIPTION

FIG. 1 is a front perspective view of our new design for a bassinet;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the figures are included for the purpose of illustrating the unclaimed portions of the bassinet and form no part of the claimed design.

1 Claim, 7 Drawing Sheets(56)
